(57) **CLAIM**

The ornamental design for a foldable, flexible, portable shadow-reducing light-emitting device, as shown and described.

DESCRIPTION

1. Foldable, flexible, portable, shadow-reducing light-emitting device

1.1: Perspective

1.2: Front

1.3: Back

1.4: Top

1.5: Bottom

1.6: Left

1.7: Right

1.8: Device in a folded configuration

1.9: Device being folded

A foldable, flexible, portable, shadow-reducing light emitting device is disclosed; it comprises a flexible fabric enclosing light strips in distinct arrays optimized for shadow reduction, and folds up and can be clasped for secure portability; it further comprises one power chord; light strips are positioned within clear, water and weather resistant chambers, and semi-rigid padding is positioned between said light strips; The broken lines in FIGS. 1.1 to 1.3 represent stitching or seams.
